DENTIST'S WHEELED OPERATORY UNIT
John Hinton Shackelford, 706 Latrobe Bldg.,
2 E. Read St., Baltimore 2, Md.
Filed Oct. 2, 1961, Ser. No. 138,344
8 Claims. (Cl. 32—22)

The present invention relates to a dentist's wheeled operatory unit and it consists in the combinations, constructions and arrangements of parts herein described and claimed.

Generally there is provided a dentist's wheeled operatory unit having the general configuration of a knee hole desk and mounted on large wheels or casters to permit it to roll forwardly and backwardly in front of a dental chair to allow patients to enter or leave the chair when the unit is rolled back, and the dentist to work conveniently and more comfortably when the unit is rolled forwardly toward the chair. The top of the operatory unit provides a large work surface or table, and sets of drawers in the unit conveniently hold instruments and dental accessories. Flexible conduits conduct hot and cold water to the unit and waste water from a sink mounted in the unit and from an adjustable cuspidor mounted thereon. The unit desirably houses an air compressor for driving pneumatic drills and instruments. The unit is optionally provided with an electric motor for propelling the unit toward and away from the dental chair. Alternatively, the unit can be made stationary and the chair movable.

There is also provided a wheel or caster mounted laboratory unit consisting of a set of matching cabinets capable of being moved to various positions and locations as desired in the dentist's office. These cabinet sections carry and house related apparatus, storage compartments for materials, and drawers for tools and instruments, etc.

In conventional dental installations, new instruments have inadvisably been hung here and there on old types and designs of fixed, rigid or immobilized dental units to the dentist's inconvenience and discomfort and at excessive expense to the profession and ultimately to the public. The mobile dentist's wheeled operatory unit herein disclosed makes these instruments more comfortably accessible to the dentist while at the same time greatly increasing his work area in front of the patient.

The costs of installation of this mobile operatory unit are extremely low, since it is necessary merely to position the unit in front of a dental chair, plug the connector of the electric cable into a conventional wall outlet and connect the flexible plumbing conduits to conventional water supply and drain devices. Removal is equally easy and simple and results in no disfigurement of the property, thus overcoming often encountered landlord objection to dentists as tenants needing permanent conventional installations that deface the property when removed.

It is accordingly an object of the present invention to provide a mobile dentist's operatory unit that requires no property disfiguring installation operations.

It is another object of the invention to provide such a unit which resembles a knee hole desk that can be moved toward or away from the patient quickly and easily.

It is a further object of the invention to provide a device of the character described which greatly increases the comfort of the dentist and ease of access to his tools and instruments by providing a large work surface and easily accessible instrument drawers and holders.

It is another object of the invention to provide a laboratory unit carried by and housed in sectionalized caster mounted cabinet sections that can be grouped or separated as desired.

Other and further objects of the invention will become

2

apparent from a reading of the following specification taken in conjunction with the drawings, in which:

FIGURE 1 is a plan view of a mobile operatory unit embodying the invention,

5 FIGURE 2 is a front elevational view of the unit of FIGURE 1,

FIGURE 3 is a rear elevational view of the unit of FIGURES 1 and 2,

10 FIGURE 4 is an end elevational view of the disclosure of FIGURE 1 from the right end of said figure,

FIGURE 5 is an end elevational view of the showing of FIGURE 1 from the left end of said figure.

15 FIGURE 6 is a fragmentary end elevational view of a second species of the propelling mechanism in section on a plane corresponding to line 6—6 of FIGURE 2,

FIGURE 7 is a fragmentary elevational view, partly in vertical section, of a third species of the electric propelling mechanism including a guiding track,

20 FIGURE 8 is a fragmentary end elevational view of a further modification of the propelling mechanism and a rack-type track therefor,

FIGURE 9 is a perspective view of a typical installation utilizing both the operatory and laboratory units of the invention,

25 FIGURE 10 is a front elevational view of one of the laboratory sections in vertical section taken on a plane immediately behind the front wall thereof,

FIGURE 11 is a side elevational view, in vertical medial section through the operatory unit, of a mobile chair embodiment of the invention, and

30 FIGURE 12 is a fragmentary side elevational view of a modified form of mobile chair.

With reference now to FIGURES 1—5 of the drawings, the numeral 11 generally designates the operatory unit as a whole. The unit 11 comprises a left cabinet section 12 and a right cabinet section 13 separately fabricated for economy of manufacture and joined together by a bridging rear panel 14 and by an opaque glass top panel 15 serving as an easily cleaned work surface. A shallow instrument drawer may be placed between cabinets 12 and 13 immediately beneath panel 15. The frame in which the drawer operates will serve with rear panel 14 to fasten sections 12 and 13 together securely at the top and back. The space between the cabinet sections and under the top panel 15 and shallow instrument drawer housing is left forwardly open to receive therein the legs and feet of a patient sitting in a conventional dental chair generally designated 16, when the unit 11 is moved to its use position shown in FIGURES 4 and 5. The numeral 17 generally designates a conventional adjustable dentist's stool.

55 The mobile operatory unit 11 is herein disclosed as being movably mounted on four rubber tired wheels 18, for which casters (not shown) could be substituted if preferred. The rear pair of wheels 18 is interconnected by a shaft 19 to which is keyed a pulley 20. A reversible electric motor 21 carries on its drive shaft a pulley 22. A belt 23 interconnects the pulleys 20 and 22 so that energization of motor 21 causes automotive movement of the unit 11 by driving the rear pair of wheels 18 in the direction desired under the control of a switch or switches 23 mounted in and on a control box 24. Power is supplied to the control box 24 and thence to the motor 21 and the other electrically powered parts of the unit 11 by a flexible cable 25 having a conventional connector plug (not shown).

60 A conventional brake or locking device, operable by a pedal 26 is associated with the right front wheel 18 to anchor the unit against unintentional movements.

65 70 A sink or lavatory 27 is located in the upper rear portion of the left cabinet section 12 and is made accessi-

ble by being mounted in or formed as a drawer slideable either laterally or rearwardly from beneath the top panel 15. Alternatively, the sink-covering part of the panel 15 could be cut out and hinged or made slideable to cover or uncover the sink 27. A conventional basin or cuspidor 28 is horizontally swingably mounted on a drain fixture 29 fastened to the upper front face of the left cabinet 12. The basin 28 includes a goose-necked faucet 30 for filling drinking cups and for flushing the basin. A flexible drain conduit 31 extends from the drain fixture 29 to a trap 32 beneath and coupled to the sink 27. Waste water from the sink 27 and the basin 28 discharges through the trap 32 into a drain conduit 33, the far end of which is easily coupled to a wall enclosed drain pipe 33a (FIG. 3).

A pair of flexible tubes 34 and 35, encased in a flexible tubular jacket 36 conduct hot and cold water from conventional faucets or couplers 36c (FIG. 3) to the faucets 30 and 37 of the basin 28 and the sink 27, respectively.

An air compressor 38 driven by an electric motor 39 is mounted in the cabinet section 12 beneath the sink 27. A hinged door 40 provides access to the compressor compartment. This equipment and placement are optional; space can serve other purposes.

An electrically heated dry heat sterilizer 41 is located in the upper forward portion of the cabinet section 12. The sterilizer 41 opens at the end of the unit 11 and the opening is closed by a hinged door having an insulating handle 43.

On the upper forward portion at the left of instrument drawers of the unit 11, there is mounted a row of bracket openings 44 for easily removably holding a plurality of power operated dental instruments collectively designated 45 and housed in a slidably mounted narrow deep drawer. Instruments 45 are here shown as being electrically energized by flexible cables 46 including take-ups 47, but optionally one or more of said tools could be pneumatically powered by compressed air from the compressor 38 or hydraulically driven by water supplied by the hoses 34 and 35.

A tier of shallow drawers 43 is slidably mounted in the front half of cabinet section 13 (FIG. 2) and above a relatively deep storage drawer 49. Behind drawers 43 and 49 is a tier of swing out drawers 50 opening at the rear of the right end of operatory unit 11.

Due to the quarter-circular shape of the swinging drawers 50, they occupy only half of the rear portion of cabinet section 13. This permits the installation of a similar tier of swinging drawers 51 through horizontal slots in the rear wall panel 14 of the unit 11 (FIG. 3). These drawers are optional. A tier of shallow drawers as in the front half of cabinet may be used to open either at end or back.

The lower front space within the cabinet section 12 and below the sterilizer 41 is occupied by the three storage drawers 52, 53 and 54 slideable through slots in the front wall of section 12 (FIGS. 2 and 5).

In the species of FIG. 6, an operatory unit 60 has a pair of its wheels 61 fixed to a shaft 62. The shaft 62 carries a pinion 63 keyed thereto. A double-acting pneumatic cylinder 64 is connected by conventional conduits and valve structures (not shown) to the air compressor 38. A piston rod 65 of the cylinder 64 has a rack 66 fixed to its outer end in a position to engage and drive the pinion 63 for moving the operatory unit 60 back and forth as indicated by the arrow 67.

In the modification of FIGURE 7, an operatory unit 70 has its wheels 71 guided in tracks 72 of U-shaped cross sections and having their ends upturned at 73 to form stops for preventing rolling of the wheels 71 off the ends of the tracks 72. One (or more) of the wheels 71 is driven by an electric motor (not shown) similar to the motor 21 (FIG. 2) which drives wheel or wheels 71 through gears 74 and 75 and a shaft 76 fixed to the wheel 71 and to the gear 75.

In the species of FIG. 8, an operatory unit 80 has its wheels 81 provided with sprocket-like teeth 82. The teeth 82 mate with cooperating depressions 83 in tracks 84. Two of the wheels 81 are fixed to a shaft 85 to which 5 is keyed a sprocket 86. A drive chain 87 couples the sprocket 86 to a sprocket 88. The sprocket 88 is fixed to the drive shaft of an electric motor 89 which is reversible to propel the unit 80 back and forth in the direction indicated by an arrow 89a.

10 With reference now to FIGURES 9 and 10, the numerals 91, 92 and 93 generally designate three separate sections of a laboratory unit. The sections 91-93 each are mounted on wheels or casters 94 to facilitate their moving to and from convenient or desired positions. Each 15 section has a pair of top drawers 95 and 96, a shallow central drawer 97 and a pair of bottom compartments closed by hinged doors 98 and 99.

A pair of sliding panels 100 and 101 of opaque glass or other suitable material covers the top of the sections 20 91-93 and provides access to apparatus housed in the top portions thereof, such as a grinder and polisher 102 in section 91. The grinder 102 has a hood and air exhaust conduit collectively designated 103.

The laboratory section 93 is shown in greater detail 25 in FIGURE 10, in which one of the upper drawers houses heating equipment 104 for impression material and the other contains a burn-out furnace 105. The elements 104 and 105 could be placed in a cabinet with a polisher also, to permit the same exhaust fan to eliminate unpleasant odors. Drawer 97 holds a plurality of impression trays 106. The lower compartments are shown as holding towels 107 and dental supplies collectively designated 108.

30 In the species of FIGURE 11, an operatory unit generally designated 110 is made stationary, being mounted on a pair of laterally disposed bars 111 serving as feet, only the far one being visible in the sectional view of FIGURE 11. A back panel 112 of metal, plastic or wood, as preferred, and a glass table top 113 correspond to like 40 parts in the mobile operatory unit of FIGURES 1 through 9.

A panel 114 defining the far left wall of the knee space under the top panel 113, has mounted thereon an angle bar 115 which together with a similar angle bar, not visible in FIGURE 11, constitutes a supporting and guiding 45 slide for a shallow drawer 116. Numerals 28' and 30' designate a swingable basin and a goosenecked faucet corresponding, respectively, to parts 28 and 30 previously described.

50 The numeral 117 generally designates a dental chair of generally known construction above its base plate 118. The base plate 118 is mounted on a plurality of low-friction rollers or casters 119 so that the chair 117 can be easily moved to and from its operatory position shown by phantom lines in FIGURE 11, in which position the front rollers engage stop blocks 120. A foot pedal 121 operates a conventional brake (not shown) for locking the rollers 119 against, or releasing the same for, movement of the chair 117. If desired, the rollers 119 can be reversibly driven by a motor (not shown) similar to the motor 21 described in the description of FIGURES 1 to 4.

55 In the species of FIGURE 12, a generally conventional dental chair 122 has its base plate 123 movably mounted on four sprocket-type wheels 124, the laterally disposed pairs of which ride back and forth on a pair of laterally 60 disposed caterpillar-type tracks each formed by a continuous sprocket-type chain 125. Each chain 125 has fixed thereto a laterally protruding stop element 126 engageable with a stop pin or post 127 to arrest the forward movement of the chair 122 in an operative position corresponding to the phantom-shown position of the chair 117 in FIGURE 11. A foot pedal 128 may be employed to operate a conventional locking and releasing brake, or a starting, stopping and reversing controller of a chair-mounted motor (all not shown).

While certain forms of the invention have been shown and described herein, it will be readily apparent to those skilled in the art that many minor modifications may be made without departing from the spirit of the invention or the scope of the appended claims.

What is claimed is:

1. A dentist's wheeled operatory unit for dental or like treatment rooms, comprising: a pair of laterally spaced cabinet structures, an elongated top member defining a large area work surface and positioned to overlie said cabinet structures and the feet of a patient seated before said operatory unit, means rigidly interconnecting said cabinet structures and said top member, wheels fixed to and supporting said operatory unit and oriented for providing rectilinear movement thereof toward and away from said patient, whereby said patient may freely approach or leave an associated treatment chair from either side thereof, a reversible electric motor mounted on said operatory unit, means drivingly connecting said motor to certain of said wheels, a swingably attached cuspidor mounted at the front of one of said cabinet structures and including a water faucet permanently mounted on said cuspidor, a sink fixedly mounted in said operatory unit and having water faucets fixedly associated therewith, and flexible conduits for fresh and waste water connected to said unit adjacent the bottom portions thereof and extending horizontally therefrom, said conduits lying loosely upon the surface of a floor supporting said unit, whereby marring of said surface is avoided.

2. Structure according to claim 1, said wheels being

30

attached to the bottom portion of said operatory unit adjacent the corners thereof.

5 3. Structure according to claim 1 additionally comprising tracks on which said wheels ride guided thereby, said tracks being free of attachment to or other marring association with the surface of said floor.

10 4. Structure according to claim 1, said cabinet structures having drawers and compartments for holding tools, instruments, materials and accessory apparatus.

15 5. Structure according to claim 1, additionally comprising a motor driven air compressor fixedly mounted in said operatory unit.

6. Structure according to claim 1, additionally comprising a set of holders mounted thereon for holding power tools, and flexible means for supplying power to said tools.

15 7. Structure according to claim 1, additionally comprising a sterilizer oven fixedly mounted in one of said cabinet structures.

20 8. Structure according to claim 1, said top member being a sheet of opaque glass.
